DESIGN FOR A BUILDING BLOCK

Ernst Steinhard, London, England, assignor to
The Marley Tile Company Limited, Riverhead,
Sevenoaks, England

Application May 20, 1940, Serial No. 92,479
In Great Britain January 30, 1940

Term of patent 14 years

To all whom it may concern:

Be it known that I, Ernst Steinhard, a citizen of the German Reich, residing at Green Gates, Craven Hill, London, W. 2, England, have invented a new, original, and ornamental Design for a Building Block, of which the following is a specification, reference being had to the accompanying drawing, forming part thereof.

Figure 1 is a perspective view of one end of a building block, showing my new design the same

being shown fragmentary for convenience of illustration;

Figure 2 is an end elevation of the building block; and

Figure 3 is a perspective view of the other end of the building block.

I claim:

The ornamental design for a building block, as shown.

ERNST STEINHARD.
